Application August 10, 1946, Serial No. 689,694

12 Claims. (Cl. 93—58)

1

This invention relates generally to the art of paper boxes and other die-cut articles, but more particularly to a novel means and method for expediting the removal of the waste which is present after die-cutting and creasing boxes and like articles from a sheet after it passes through the creasing and cutting machine.

It has for its primary object to provide an efficient means and method for removing such waste which is so designed as to receive the cut and printed sheets of multiple boxes or other die-cut articles as they are continuously discharged from the machines for so doing, thereupon feeding such sheets to a stripping station to cause the relative displacement of the die-cut portions of the sheet from the waste portions surrounding the same and in directions to strip such portions from each other, and then conveying the die-cut blank portions and the stripped waste portions to different points of discharge.

Another object of the invention is to provide a novel, simple and efficient machine of this character which is so constructed as to cause the die-cut blank and waste portions of the sheets to be respectively conveyed in receding directions while being retained on companion relatively movable means and which results in the stripping of the waste from the die-cut portions of the sheets with such respective portions being thereupon conveyed to different points of discharge.

A further object is to provide a machine of this character whose die-cut blank and waste engaging members for retaining the companion portions of the sheets to the relatively movable means and for stripping those portions from each other sized and different shaped boxes or other articles.

Other features of the invention reside in the construction and arrangement of parts herein-after described and particularly pointed out in the appended claims.

In the accompanying drawings:

Figure 1 is a fragmentary top plan view of the machine embodying our invention, the conveyor belts being omitted. Figure 2 is a fragmentary front view thereof with such belts likewise omitted. Figure 3 is a cross section taken substantially in the plane of line 3—3, Figure 2. Figure 4 is a fragmentary cross section taken substantially in the plane of line 4—4, Figure 2. Figures 5 and 6 are enlarged fragmentary cross sections showing the starting and finishing operations in effecting the stripping of the waste from the box portion of the sheet. Figure 7 is an enlarged fragmentary longitudinal section showing one of the

2

sheet stops of the machine. Figure 8 is a fragmentary elevation of the drum of the machine, partly broken away to show the gripper finger mountings and associated parts. Figure 9 is an enlarged cross section taken substantially in the plane of line 9—9, Figure 8. Figure 10 is a fragmentary sectional diagrammatic or perspective view showing the manner in which the sheets are fed to the machine for stripping the waste from the box or die-cut portions of the sheet and how the respective portions are discharged. Figure 11 is a diagrammatic sectional elevation showing one form of stacking apparatus which may be used in conjunction with our machine for receiving the boxes or like articles from which the waste has been removed, one of the box-sections having been picked up from the delivery belt. Figure 12 is a similar view but with a box-section being shown ready to be deposited on the stack or pile. 20 Similar characters of reference indicate the corresponding parts throughout the several views.

In its general organization our waste removing machine, which may be either employed as a separate unit or adapted for direct operative association with or attached to a box-creasing and cutting machine, consists of relatively movable means between which the printed, creased and cut box sheets are presented for stripping the waste from the box-containing portions thereof; means disposed in correlation to said relatively movable means and engageable with the opposite sides of the sheet for causing the retention of the die-cut article or box-containing portion of the sheet on one of such movable means and the retention of the waste portion of the sheet on the companion movable means, whereby, as the box-containing portion travels coextensively with one of the movable means and the waste portion is conveyed in a receding direction from such companion movable means about the cut lines on the sheet from the box portion thereof, the respective portions are thereupon conveyed to separate points of discharge; and means for adjusting those parts of the machine engageable with the waste and box-containing portions of the sheets to readily adapt the machine for operation on different sizes and shapes of boxes.

Referring now to the drawings and particularly to Figure 10 which more or less diagrammatically depicts the method and one form of unit or machine for expediting the removal or stripping of the waste from the box-containing portions of a sheet, the numeral 15 indicates generally the sheet which has been printed, creased and cut to form a multiple of boxes therefrom, 16 indi-

cates the box-containing portions thereof, and 17 indicates the waste portion, which, in the example shown, is the marginal waste bordering the sheet about its box-containing portion. It will also be noted in this figure that the sheets are fed or delivered to the waste stripping station of the machine or a movable member or conveyor 18 consisting of a series of transversely spaced bands and it will be further observed that this same conveyor serves to carry the box or other die-cut portions from which the waste has been removed to a point of discharge, and may if desired, be the same conveyor associated with the machine which creases and cuts the box-forming sheets.

By way of example, the machine or unit for expediting the removal of the waste from the box-forming sheets consists of a suitable frame including end plates 19, which may be attached to the frame of a box making machine or which may be made as a separate unit in operative relation to such machine, and an intermediate plate 20, these plates being secured in proper horizontally-spaced relation by tie rods or bolts 21. Journalized in suitable bearings applied to these frame-plates is a horizontal shaft 22 which constitutes the drive shaft of the machine and which may be actuated intermittently in any approved manner, motion being transmitted to such shaft when passing a sheet through the machine to strip the waste from the box-forming body thereof. In the drawings, by way of example, the shaft is provided on one end with an automatic intermittent feed control assembly 23 of any suitable construction and a drive sprocket 24 for connecting it to any suitable source of power. On its other end this shaft has a second sprocket 25 from which power is transmitted to other operative parts of the machine as will hereinafter appear. For the purpose of arresting the shaft, at a predetermined point after each operating cycle thereof, a stop wheel 26 is fixed thereon with which a stop dog 27 is adapted to releasably interlock when the control assembly 23 is disengaged from coupling engagement with the shaft. Mounted on the shaft between one of the frame plates 19 and the intermediate plates 20 is a waste conveying member or drum 28 disposed with its lower side in substantially tangential relation to the conveyor 18 and forming therewith what we shall refer to as the stripping station, the sheet 15 being fed or presented between these relatively movable conveying members and then operated on in a manner to cause the box-containing portion 16 of the sheet to be retained flatwise on or in parallel relation to the conveying member 18 and the waste portion 17 of the sheet to be retained on the companion conveying member 28 and follow in the revolving path thereof or in a direction away from such conveyor member 18 to cause the stripping of the waste portion of the sheet from its box-containing portion. When these sheet portions are so stripped from each other as depicted in Figure 10, the box-containing portion is delivered by the conveyor member 18 to a point of discharge while the stripped waste portion is delivered to a point of discharge by a conveyor or apron 29 disposed in operative relation to the conveying member 28 and in a plane above and substantially parallel to the discharge end of the companion conveying member.

The band conveyor 18 travels intermittently relatively to the drum conveyor 28, being driven by any suitable means, and is guided on rollers 30, 31, and 32. Extending part way about the drum conveyor are a plurality of transversely-

spaced bands or belts 33 which pass at their other ends about a roller 34, fixed on a shaft 35 journaled in the upper ends of the frame-plates 19 and against which belts the upper sides of the sheets 15 bear in passing through the machine. It will be noted in Figures 5 and 6 that the feed end of the waste discharge apron 29 travels concentrically with the contiguous portions of the drum-engaging bands 33 and that the waste portion 17 of the sheet is guided and confined for a short distance of travel between such bands and apron, this waste portion being more or less skeleton or border-like in shape and requiring extensive support while traveling from the drum to the horizontal stretch of the discharge apron. The latter is guided on suitable rollers 36, 37, 38 suitably supported on the frame of the machine, the roller 36 being fixed to a driven shaft 39 journaled at the lower end of such frame, while the adjoining roller 31 in operative engagement with the band conveyor 18 is fixed on a parallel driven shaft 40. This band conveyor, the drum bands 33 and the discharge apron 29 travel in the same direction and at the same speed and motion is transmitted thereto from the drum-shaft 22. For this purpose, as shown in the drawings, a sprocket drive 41 is provided from the sprocket 25 on the drum-shaft to the upper roller-shaft 35 and a second sprocket drive 42 is provided from the latter to the lower roller shaft 40, while a spur gear 43 on the latter meshes with a like gear 44 on the apron roller shaft 39 to propel the apron 29. Thus, during the operative cycle of the machine, which is somewhat less than a complete revolution of the drum conveyor 28, the sheet 15 is automatically propelled therethrough and the waste portion stripped therefrom by the mechanism presently to be described.

As the sheet is delivered to the drum conveyor 28 by the horizontal band conveyor 18, and at which time the former is at rest, its leading edge encounters a series of stop fingers 45 disposed in a row transversely beneath the drum and in certain of the spaces between the bands of the conveyor 18 and yieldingly mounted on the free ends of companion vertically-swinging stop levers 46 applied to a horizontal rock shaft 47 supported at its ends in the frame-plates 19. Each stop finger projects above the top face of its attaching lever, as shown in Figure 7, and is urged toward its normal position in abutting relation to the end of its lever by a spring 48 which also serves to allow the stop finger to yield slightly forwardly as the leading edge of the sheet encounters it. At the start of the operating cycle of the machine, these fingers are swung downwardly or below the plane of the band conveyor to permit the sheet to enter the stripping station, and this disappearing action is effected by a cam 49 fixed on the drum-shaft 22 and with which a follower arm 50, radiating from the rock shaft 47 engages, so that at predetermined times the stop fingers are projected into and out of their operative position. A spring 51 connected at one end to the follower arm 50 and at its other end to one of the tie rods 21 of the frame serves to constantly urge such arm toward the peripheral edge of the cam.

As the sheet 15 approaches the drum conveyor 28 its top and bottom surfaces engage two rows 70 of oppositely-displaceable contacting or bearing fingers 52 and 53, respectively, located at the feed side of such conveyor, these fingers being disposed transversely in rows slightly to the rear of the stop fingers 45 and in certain of the spaces 75 provided by the band conveyor 18.

The top or break-down fingers 52 are mounted on a rock shaft 54 disposed outwardly of and parallel to the stop finger shaft 41 and are so positioned and adjustably set thereon by bolts or the like to engage the top side of the box-containing portion 16 of the sheet, that is, to maintain such portion of the sheet flatwise against the band conveyor and exert a downward pressure thereon relative to the waste portion 17 of the sheet. This break-down pressure is effected by a cam 55 fixed on the drum shaft 22 and engaged by a follower arm 56 radiating from the rock shaft 54, so that at predetermined times the fingers 52 are pressed downwardly firmly against the sheet, a spring 57 connected at one end to the follower arm and at its other end to one of the tie rods 21 serving to constantly urge the arm toward the peripheral edge of the cam.

The lower or sheet-lifting fingers 53 are mounted on a rock shaft 58 disposed parallel to but below the companion rock shaft 54, and are so positioned or set thereon to engage the bottom side of the waste portion 17 of the sheet being operated upon, and thereby tend to lift such portion toward the drum or in a direction opposite to that in which the break-down fingers 52 operate and thereby cause a separation or stripping of the box-containing portion of the sheet from its waste portion. In the example of the sheet shown in Figure 10, the waste portion 17 is a marginal or rim-like area and the lifting fingers 53 are disposed as to engage the side pieces of such portion. The movement of these fingers toward the sheet is effected by a cam 59 fixed on the drum shaft alongside the cams 49 and 55 and engaged by a follower arm 60 radiating from the rock shaft 58 and having a spring 61 connected thereto for constantly urging it toward the peripheral edge of the cam. A second set of waste lifting or guiding fingers 62 is provided at the discharge side of the drum conveyor and longitudinally in line with the companion lift fingers 53 for the purpose of holding the stripped waste portion of the sheet against such conveyor as it travels upwardly therewith. These fingers 62 are mounted on a rock shaft 63 and a spring-pressed follower arm 64 radiating from said shaft engages a cam 65 disposed alongside the companion cams 49, 55, and 59 to control the movement of such fingers toward and from the drum conveyor. It will be noted, in Figures 5 and 6, that these fingers terminate short of the lower or leading portion of the discharge apron 29 and that from such point the waste portion of the sheet travels between the drum-engaging belts 33 and the contiguous portion of such apron until it reaches the longitudinal stretch of the latter when it is carried along therewith in an obvious manner to a point of discharge.

Means are provided on the drum conveyor 28 for gripping the leading and trailing edges of the sheets 15 to thereby effectually retain such ends, which constitute a part of the waste portion 17, to the face of the drum or against the belts 33 engaging the same and compel movement of such sheet portion with the drum conveyor. For this purpose we provide two sets of gripper fingers 66, 67 disposed in rows in suitable spaced relation lengthwise of the drum conveyor and projecting outwardly from the periphery thereof, the gripper fingers 66 being engageable with the leading end of the sheet and the fingers 67 being engageable with the trail-

ing end of the sheet, as shown in Figures 6 and 9. The leading gripper fingers 66 are mounted on a longitudinal rock shaft 68 disposed parallel to the drum shaft 22 and suitably supported on the drum conveyor so that when such shaft is rocked in one direction the free or curved ends of the gripper fingers clamp the sheet to the drum while when rocked in the opposite direction the fingers are released. For the purpose of thus controlling these fingers a cam 69 is fixed on the inner face of the intermediate frame plate 20 and movable about the periphery of the same with the movement of the drum is a follower arm 70 radiating from the rock shaft 68. The gripping ends of the fingers extend through a longitudinal slot 71 formed in the surface of the drum.

The companion or trailing gripper fingers 67 are mounted in a like manner but are adjustable circumferentially relative to the drum so as to be properly set in accordance with the length of the box-forming sheets being operated upon. For this purpose, these fingers are mounted on a longitudinal rock shaft 72 supported in the outer ends of the two or more radial arms 73 applied to the drum shaft 22, as shown in Figures 8 and 9, and their gripping ends extend through companion circumferential slots 74 formed in the surface of the drum. Adjustment of this set of gripper fingers in proper spaced relation to the companion set of gripper fingers 66 is effected from a hand-operated shaft 75 supported in the drum and having two or more pinions 76 thereon meshing with complementary segmental gear racks 77 attached to the arms 73. Between its ends the drum has recessed or notched reinforcing partitions 78 therein and one end of the rock shaft extends through an arcuate slot 79 in that end of the drum adjoining the frame plate 20 and has a follower arm 80 thereon engaging a cam 81 fixed on such plate alongside the companion cam 69 for controlling the rocking of the shaft 72 and accordingly the gripping and releasing positions of the fingers 67. The timing of the gripping fingers is such that the fingers 66 grip the leading edge of the sheet at the start of the stripping operation and are released as such edge of the stripped waste portion of the sheet is directed onto the receiving end of the horizontal stretch of the discharge apron 29, while the companion fingers 67 grip the trailing edge of the sheet as it reaches the stripping station and hold it to the drum until it reaches the discharge apron where they are released. At this time the drum is stopped and the leading gripper fingers 66 in position for gripping the next sheet entering the stripping station.

Referring now to Figures 11 and 12, showing one form of apparatus which may be employed for receiving the boxes or other die-cut articles from the waster-removing machine, and piling them in orderly fashion for subsequent packing and delivery, the numeral 82 indicates a horizontally reciprocating carriage guided on a track 83 and on which the conveyor bands 18 are mounted, this carriage serving to present the die-cut article to the waste removing machine and to receive the body 16 of the article, from which the waste has been removed, and thence present such article-body to the apparatus indicated generally by the numeral 84 for stacking them in a pile. This carriage includes a vacuum chamber 85 having perforations 86 in its top wall for retaining the article-bodies 16 thereon until they

reach the piling or stacking apparatus, when the vacuum is shut off and the bodies are engaged or gripped by overhead vacuum cups 87 mounted on a vertically-reciprocating guide frame 88 actuated in any approved manner to lift such bodies from the conveyor belts 18. In Figure 12, a group of article-bodies 16 have been presented to this apparatus and they have been lifted from the conveyor 18 by the vacuum cups. In this position of the parts it will be further noted that a 10 box sheet is being presented to the waste stripping machine. On the return stroke of the carriage 82, the conveyor 18 and the vacuum chamber 85 are removed from the stacking apparatus, enabling the frame 88 to be lowered to the 15 position shown in Figure 12, immediately above the stacking platform 89, at which time the vacuum is released from the cups 87 and the box-bodies drop a short distance by gravity onto the platform. Before the next forward cycle of the carriage, the cup-frame is raised to the position shown in Figure 11, in readiness to receive the next delivery of article-bodies.

We claim as our invention:

1. In a machine for stripping the waste from a die-cut sheet, comprising relatively movable members between which the sheet is adapted to be presented and against which the die-cut and waste portions of the sheet are respectively urged for stripping such portions from each other upon the relative movement of said members, means on one of said members for releasable gripping engagement with the waste portion of the sheet, and means disposed at the approach side of said members and engageable with the opposite surfaces of the die-cut and waste portions of the sheet for urging them toward said members, respectively.

2. In a machine for stripping the waste from a die-cut sheet, relatively movable linear and angular members disposed in tangential relation and between which the sheet is adapted to be presented, means disposed in correlation to the approach between said members for causing the pressing of the body of the die-cut sheet against one of the members and the pressing of the waste portion of the sheet against the other of such members, and means on one of said members for releasable gripping engagement with the waste portion of the sheet for conducting such waste portion away and stripping it from the die-cut portion thereof.

3. In a machine for stripping the waste from a die-cut sheet, a conveyor for delivering the sheet to and from a predetermined station, a movable waste-gripping member disposed at such station in correlation to said conveyor for conducting the waste of the sheet in a direction away and stripping it from the die-cut portion thereof, and means in advance of said waste-gripping member and engageable with the top and bottom surfaces of the die-cut portion and waste of the sheet, respectively, for depressing the die-cut portion into surface engagement with said conveyor and the waste of the sheet toward said movable member.

4. In a machine for stripping the waste from a die-cut sheet, a conveyor for the sheet, a second conveyor disposed in correlation to the first conveyor including means for releasably gripping and conducting the waste in a receding direction therefrom, and means in advance of said second conveyor and above and below the first conveyor and operatively engageable with the top and bottom surfaces of the die-cut portion of

5 said sheet and said waste, respectively for causing the die-cut portion of the sheet to be pressed downwardly against the first-named conveyor and the waste to be pressed upwardly against 10 said second conveyor to thereby strip the waste from the die-cut portion of the sheet.

5. In a machine for stripping the waste from a die-cut sheet, comprising relatively movable members between which the sheet is adapted to be presented, one of said members consisting of a conveyor belt for flatwise supporting the sheet before and after stripping the waste therefrom and the companion member including a drum disposed in substantially tangential relation to the belt including means for releasably gripping and conveying the waste of the sheet away from the belt as it is stripped from the sheet by the relative movement of said members, and means in operative relation to the drum for pressing the waste against the same during its stripping from the sheet.

6. In a machine for stripping the waste from a die-cut sheet, comprising relatively movable members between which the sheet is adapted to be presented, one of said members consisting of a conveyor belt for flatwise supporting the sheet before and after stripping the waste therefrom and the companion member including a drum having releasable waste gripping means thereon 25 and disposed in substantially tangential relation to the belt for receiving and conveying the waste of the sheet away from the belt as it is stripped from the die-cut portion of the sheet by the relative movement of said members, and opposing 30 movable means adjacent the approach side of the drum in correlation to the conveyor belt and the drum and engageable with the opposite surfaces of the die-cut sheet for causing a relative displacement of the die-cut and waste portions of 35 the sheet toward said belt and said drum, respectively, to strip the one portion of the sheet from the other.

7. In a machine for stripping the waste from a die-cut sheet, comprising relatively movable members between which the sheet is adapted to be presented, one of said members consisting of a conveyor belt for delivering the sheet to the stripping station and for discharging the die-cut portion of the sheet from such station and 45 the other member consisting of a rotatable drum having means thereon for releasable gripping engagement with the leading and trailing edges of the waste portion of the sheet for conveying it in a direction away from said conveyor belt, and 50 means in advance of said drum and engageable with the opposite surfaces of the sheet for urging its die-cut portion toward the belt and its waste portion toward the drum.

8. In a machine for stripping the waste from a die-cut sheet, comprising relatively movable members between which the sheet is adapted to be presented and to which the die-cut and waste portions of the sheet are respectively retained for stripping such portions from each other 55 upon the relative movement of said members, oppositely-displaceable means disposed above and below the path of movement of the sheet in advance of its presentation to said members and engageable with the die-cut and waste portions thereof respectively, for urging the former flatwise toward one of said movable members and the latter in the opposite direction toward the other of said members to effect a stripping action, means connected to said displaceable means for actuating them at predetermined times, and 60

waste gripping means applied to said last-named movable member and releasably engageable with the leading and trailing ends of the waste portion of the sheet.

9. In a machine for stripping the waste from a die-cut article-forming sheet, comprising relatively movable members between which the sheet is adapted to be presented and to which the die-cut and waste portions of the sheet are respectively retained for stripping such portions from each other upon the relative movement of said members, oppositely-displaceable means disposed above and below the path of movement of the sheet and engageable with the top and bottom surfaces of the die-cut and waste portions thereof, respectively, for urging the former flatwise toward one of said movable members and the latter in the opposite direction toward the other of said members to effect a stripping action, waste-gripping means applied to said last-named movable member and releasably engageable with the leading and trailing ends of the waste portion of the sheet, means connected to said displaceable means for actuating them at predetermined times, and means disposed in correlation with said last-named movable member for flatwise guiding and directing the stripped waste portion to a point of discharge.

10. In a waste stripping machine, a conveyor for the die-cut sheet, a revolving drum disposed in operative relation thereto and between which parts the sheet is presented with the die-cut portion traveling with the conveyor and the waste portion traveling in a receding direction therefrom with the drum, means disposed at the advance side of the drum and engageable with the opposite surfaces of the sheet for urging the die-cut portion thereof against said conveyor and the waste portion against said drum, means disposed at the discharge side of the drum for engagement with the waste portion of the sheet for holding it against said drum, and a second conveyor spaced from the first-named conveyor and in operative relation to the other side of said drum for directing and guiding the stripped waste portion of the sheet against the drum to a point of discharge, said first-named conveyor also directing the die-cut portion of the sheet stripped of its waste to a point of discharge.

11. In a waste stripping machine, a conveyor for the die-cut sheet, a revolving drum disposed in operative relation thereto and between which parts the sheet is presented with the die-cut portion traveling with the conveyor and the waste portion traveling in a receding direction therefrom with the drum, lift and stripper fingers disposed in advance of said drum and engageable with the opposite surfaces of the waste and die-cut portions of said sheet, respectively, as the sheet is fed between the conveyor and the drum

for effecting a stripping action on such sheet portions, gripper fingers on said drum and releasably engageable with the leading and trailing edges of the waste portion of the sheet for retaining it to the face of the drum, means operatively connected to said lift and stripper fingers and to said gripper fingers, respectively, for actuating them, a discharge conveyor in operative relation to the discharge side of said drum for directing the waste portion therefrom, and guide fingers disposed in operative relation to the drum and in advance of said discharge conveyor for guiding and directing the waste portion of the sheet between the drum and the adjoining portion of said discharge conveyor.

12. In a waste stripping machine, a feed conveyor composed of spaced bands for the die-cut sheet, a revolving drum disposed in operative relation thereto and between which parts the sheet is presented and propelled with the die-cut portion adapted to travel with the conveyor and the waste portion adapted to travel in a receding direction therefrom with the drum, a waste discharge conveyor disposed above the feed conveyor at the discharge side of the drum and having a stretch thereof disposed about the adjoining side of the drum for the passage of the waste portion therebetween, lift and stripper fingers disposed in advance of the drum below and above the plane of the feed conveyor for engagement with the opposite surfaces of the sheet and displaceable in the spaces between the bands thereof for urging the waste and die-cut portions of the sheet in opposite directions toward the drum and feed conveyor, respectively, to effect a stripping action of such portions from each other, gripper fingers mounted in circumferentially spaced relation on said drum for releasable engagement with the leading and trailing edges of such waste portion of the sheet, guide fingers disposed at the discharge side of the drum for contact with the stripped waste to urge it toward the drum and between the latter and the adjoining stretch of the discharge conveyor, and means for governing the actuation of said several fingers to and from their operative positions.
